(57) **CLAIM**

The ornamental design for a vent clip, as shown and described.

DESCRIPTION

FIG. 1 is a top plan view thereof of a vent clip, the bottom plan view being a mirror image of the top plan view shown;

FIG. 2 is a front elevational view thereof;

FIG. 3 is a rear elevational view thereof;

FIG. 4 is a left side elevational view thereof, the right side elevational view being a mirror image of the left side elevational view shown; and,

FIG. 5 is a rear, top, and left side perspective view thereof.
